UNITED STATES PATENT OFFICE.

EUGEN SCHAAL, OF STUTTGART, WÜRTEMBERG, GERMANY.

COMPOSITION FOR SOAP.

SPECIFICATION forming part of Letters Patent No. 319,854, dated June 9, 1885.

Application filed March 27, 1885. (Specimens.)

To all whom it may concern:

Be it known that I, EUGEN SCHAAL, a subject of the King of Würtemberg, residing at Stuttgart, in the Kingdom of Würtemberg and German Empire, have invented new and useful Improvements in Compositions for Soaps, of which the following is a specification.

This invention relates to a soap composition in which petrol acid forms one of the ingredients.

In carrying out my invention I prepare petrol acid by the following process: I take, say, five hundred pounds of petroleum, composed of hydrocarbons, the boiling-point of which varies between 150° and 400° centigrade, and bring the same into a metallic retort provided with a suitable agitator and with a cooling-tube, which is upwardly inclined or otherwise arranged so that the liquid which results from the condensation of the vapors runs back into the retort. To the petroleum I add from twenty to thirty pounds of an alkaline substance—such, for instance, as oxide of calcium or caustic soda, or a mixture prepared of equal parts of oxide of calcium, caustic soda, and carbonate of soda—and then the retort is heated so as to cause the mass to boil violently under constant stirring, while at the same time a current of atmospheric air or oxygen is passed through the mixture by means of an air-pump or otherwise. After the boiling has continued for about half an hour (more or less) an additional quantity of alkali is introduced, which may be effected through the cooling-tube in a manner well known to chemists. The whole quantity of alkali employed may be as much as one hundred and twenty-five pounds, or twenty-five per cent. of the petroleum used. The supply of the alkali must be regulated so as to have some free alkali present during the entire process of conversion. By the action of the oxygen the petroleum is converted into acids, which, being mostly insoluble in the remaining liquor, are precipitated to the bottom of the retort.

Different kinds of petroleum, earth-oils, brown coal-oils, or similar hydrocarbons may be converted into soap in the manner above described.

From these soaps the organic acids contained therein are separated, and an acid mixture is obtained which contains solid and liquid petrol acids. In preparing soaps suitable for cleaning floors, tinware, coarse metals, washing greasy garments, or for laundry purposes in general I can use either the solid or the liquid petrol acid.

In order to prepare soap I take a quantity of petrol acid and boil the same together with a suitable quantity of caustic alkali or of the carbonate of an alkali. The liquid petrol acids appear to form a homologue series having the general formula $C_nH_{2n-2}O_2$ —for instance, $C_9H_{16}O_2$, $C_{10}H_{18}O_2$, &c. In order to form a soap from an acid composed of $C_9H_{16}O_2$, one equivalent of sodium hydroxide ($NaOH$) is required, or about forty pounds of sodium hydroxide to one hundred and fifty-six pounds of the acid; but this proportion varies according to the kind of soap to be produced. The solid petrol acids are poorer in hydrogen and richer in oxygen than the liquid petrol acids. They contain from three to four atoms of oxygen. The magnesium salt of a solid petrol acid contains—

C = 57.903 Mg = 2 C = 10.62 Equiv.

H = 7.313 H = 16.1

Mg = 6.541 Mg = 1.

O = 28.243 O = 3.88

75

100.000

The silver salt of a solid petrol acid contains—

C = 58.155 Ag = 108 C = 22.36 Equ.

H = 6.053 H = 17.92

Ag = 23.410 Ag = 1.

O = 12.382 O = 3.57

80

100.000

The soaps obtained from the saponification of petrol acid are not so hard as those of hard fats, and they are not rendered quite so insoluble by the action of salt as the soaps of hard fats. For this reason they can be used with advantage for washing in salt water. In other respects they resemble, essentially, the soaps prepared from oleic acid; but the petrol acids differ from the acids series, inasmuch as the same, when brought together with halo-

gens, do not form any substitution products, and that by the action of nitric acid the formation of elaidine does not occur.

What I claim as new, and desire to secure 5 by Letters Patent, is—

1. As an ingredient in the composition of soap, the petrol acid herein specified.
2. A soap composed of the petrol acid herein specified and a saponifying alkali, substantially as and for the purpose described.

In testimony whereof I have hereunto set my hand and seal in the presence of two subscribing witnesses.

EUGEN SCHAAL. [L. S.]

Witnesses:

FRIEDRICH OEHM,
T. ROENHEIM.
